Inventor

H. C. DENTURK

By *J. Derby W.* Attorney

UNITED STATES PATENT OFFICE.

HENRY C. DENTURK, OF HUNTINGTON, NEW YORK.

DIRIGIBLE AIRSHIP.

Application filed September 8, 1924. Serial No. 736,577.

To all whom it may concern:

Be it known that I, HENRY C. DENTURK, a citizen of the United States, residing at Huntington, Long Island, in the county of 5 Suffolk and State of New York, have invented certain new and useful Improvements in Dirigible Airships, of which the following is a specification, reference being had therein to the accompanying drawings.

10 This invention relates to certain new and useful improvements in dirigible airships, the object being to provide an airship with gas bags enclosed in elongated chambers so that the bags will be protected and in case 15 of leakage, the gas will be confined within the chambers to support the airship.

Another and further object of the invention is to provide an airship which is exceedingly simple and cheap in construction, 20 the same being provided with sustaining planes tapering to increase the speed, the entire body of the ship being pointed to offer the least resistance possible.

A still further object of the invention is 25 to provide an airship in which the body is mounted on carriages, the same being provided with a pilot cabin from which extends a vertical passage to a bridge formed on top of the plane so as to allow the passengers to 30 reach the bridge in case of an accident.

A still further object of the invention is 35 to provide additional planes for carrying additional weight, said planes being pivotally mounted so that they can be raised and lowered if desired.

Other and further objects and advantages of the invention will be hereinafter set forth and the novel features thereof defined by the appended claims.

40 In the drawings,

Figure 1 is a side elevation of an airship constructed in accordance with my invention;

Figure 2 is a top plan view showing the 45 tapering construction; and

Figure 3 is a transverse section showing the frame construction.

In carrying out my invention I employ a 50 pair of spaced rectangular frames 1 and 2 connected together by braces 3, said frames being extended to form the bow 4 of the airship. These frames are covered with suitable material impervious to air and gas so as 55 to form air tight chambers in which are disposed cylindrical gas bags 5 and 6.

By this construction the gas bags 5 and 6

are enclosed in tight chambers so as to protect the bags and to provide air tight chambers for retaining the gas in case one of the bags should become punctured, thereby providing a pair of sustaining chambers for supporting the airship.

Extending from the sides of the chambers are tapering sustaining planes 7 and 8 connected to the frames by stay wires 9 and as 60 shown in Figure 2, these planes are tapering so as to provide a tapering design.

Arranged beneath the frames in a pilot's cabin 10 to the front and rear of which are arranged carriages 11 and 12 for supporting 70 the airship and to allow it to move freely over the ground in starting and alighting. Extending upwardly from the top of the cabin 10 is a vertical passage 13 to a bridge 14 formed on top of the airship, through 75 which access to the cabin can be obtained so that in case of accident the passengers of the airship can reach the top of the plane, which is especially of advantage in case the airship should drop into the water, in which 80 event the air tight chamber would support the airship.

The airship is provided with additional folding planes 15 and 16 so as to support the bridge when desired, said planes being pivotally mounted and connected to a suitable winding mechanism not shown by wires 17.

The front and rear of the airship are provided with propellers 18 and 19 for driving the plane, suitable engines being arranged 90 within the cabin or at any other desired point.

From the foregoing description it will be seen that I have provided an airship mounted on wheels having spaced chambers to receive gas bags and provided with sustaining planes in order to form an airship having great speed, the construction of the same being such that the pilot is arranged beneath the chambers and a passage is formed 100 for entering the pilot's cabin from above and below.

What I claim is:

1. A dirigible airship comprising a pair of substantially rectangular frames spaced 105 apart and having a covering impervious to air and gas to form elongated chambers, gas bags arranged in said chambers, tapering sustaining planes arranged to each side of said bags and said chambers and folding 110 planes arranged to each side of said tapering planes.

2. A dirigible airship comprising a pair of substantially rectangular frames spaced apart and having a covering impervious to air and gas to form elongated chambers, gas bags arranged in said chambers, tapering sustaining planes arranged to each side of said bags and said chambers, folding planes

10
of said airship.

5 In testimony whereof I hereunto affix my signature.

HENRY C. DENTURK.
